(57) **CLAIM**

The ornamental design for a track-lighting fixture, as shown and described.

DESCRIPTION

FIG. 1 is a front elevational view of a track-lighting fixture showing our new design;
FIG. 2 is a top, front, and right side perspective view thereof;
FIG. 3 as a rear elevational view thereof;
FIG. 4 as a right-side elevational view thereof;
FIG. 5 as a left-side elevational view thereof;
FIG. 6 as a top plan view thereof; and,
FIG. 7 as a bottom plan view thereof.

The broken-line disclosure in the views is understood to represent portions of the article which form no part of the claimed design.
